UNITED STATES PATENT OFFICE.

LOUIS GUICHARD, OF PARIS, FRANCE.

DISTRIBUTION MECHANISM OF INTERNAL-COMBUSTION MOTORS.

1,207,164.

Specification of Letters Patent. Patented Dec. 5, 1916.

Application filed December 23, 1913. Serial No. 808,894.

To all whom it may concern:

Be it known that I, LOUIS GUICHARD, a citizen of the Republic of France, residing at 1 Avenue Peterhof, Paris, France, have 5 invented certain new and useful Improvements in the Distribution Mechanism of Internal-Combustion Motors, of which the following is a specification.

My invention has for its object improvements in so called valveless internal combustion motors and is applicable to the type of motors wherein a cylindrical reciprocating sleeve is employed in place of the usual 10 puppet valves. In the known distributing mechanisms of this type, the sleeve is usually subjected to non-symmetrical forces due to the non-symmetrical arrangement of the actuating mechanism relatively to the axis of the sleeve, with the result that jamming occurs which consumes a portion of the power 15 and produces an oval wear of the parts. Moreover the shocks and abnormal frictional strains between the piston and the sleeve and other members, cause after a certain lapse of time, an excessive amount of 20 "play" which gives rise to noise in working. Further, in a certain number of motors having a cylindrical reciprocating sleeve the latter is exposed to the pressure 25 of the gas over its entire lower edge. According to my invention, the sleeve is hung freely on diametrically opposite ends of an oscillating frame wherein the sleeve is able by the action of its own weight to keep its 30 vertical position at all times, and the mechanism for actuating the sleeve engages the frame at two opposite ends of a diameter at right angles to the diameter of free suspension. Moreover, the sleeve thus freely sus- 35 pended, executes its reciprocating movements in a cylindrical chamber which is closed, *i. e.*, isolated from the combustion of the motor, so that the gases can only act 40 through the distributing parts upon the sleeve.

A practical embodiment of my invention is illustrated by way of example in the accompanying drawings.

Figure 1 is a diagrammatic elevation of 50 the general arrangement of an internal combustion motor fitted with the improved distributing mechanism. Figs. 2 and 3 are two longitudinal sections taken at right angles to each other, respectively along the suspension axis of the sleeve, and along the axis to whose ends the rocking beam, in the form

of a frame, is connected to the usual actuating parts; these sections are taken respectively on the lines A—A and B—B of Fig. 4. Fig. 4 is a horizontal section on the line C—C of Fig. 3. Fig. 5 is a horizontal section on the line D—D of Fig. 3. Fig. 6 is another diagrammatic view showing the modification of the suspension of the annular sleeve, Fig. 7 is a similar view as Fig. 65 6 showing a slight modification.

In these several figures, *a* is the motor cylinder in which works a piston *b*.

c is the end of the combustion chamber formed in the usual manner on a removable head.

d is the cylindrical distributing sleeve capable of reciprocating.

v designates one or more apertures through which the oil for lubricating the sleeve can 75 flow and return into the lower framing.

According to my invention, the sleeve *d* is freely suspended so as to be capable of oscillating, for instance, by means of two pins or trunnions *d'* in suitable bearings *e'* 80 provided on an oscillating frame *e*. By means of this frame, the sleeve is connected to the actuating mechanism *f*—*g* which is attached to the said frame in an axis *x*—*x* (Fig. 4) that is at right angles to the pivotal or suspensory axis *d'*—*d'*. As will be readily perceived, this manner of suspension, permits of reciprocating the sleeve without exerting any oblique strain upon the body of the sleeve, as the force for reciprocating the sleeve is always exerted upon the trunnions *d'*—*d'* in the vertical axial plane common to the cylinder and the sleeve, while the latter, due to its being freely suspended, will automatically center 90 itself in all positions. Moreover, also according to my invention, the sleeve *d* is guided in a cylindrical chamber *h* formed between the outer wall of the head *c* and an extension of the wall of the cylinder *a*. This chamber *h* completely isolates the sleeve from the combustion chamber of the cylinder. As a result of this construction the gases can act upon the sleeve *d* only inside the distribution parts *i*—*j* (Fig. 1). Further, the inconsiderable strains to which the sleeve is still subjected, may be balanced in the usual way by providing an opening of sufficient area in the removable head *c*.

The reciprocation of the sleeve through the medium of the frame *e*, may be effected.

for instance by means of two connected rods *f*, *g*, connected to the eccentrics *s*, *t*, (Fig. 1) on shafts *m* and *k* which are rotated at speeds having the ratio of two to one. For this purpose an arrangement may be employed, for instance, such as that indicated in the diagrammatic Fig. 1, where the shafts *m* and *k* are connected to the motor shaft *n* by means of a chain *o* and toothed sprocket 10 wheels *p*, *q*, *r* of suitable diameters, the wheels *q* and *r* having for instance equal diameters while the wheel *p* has a diameter twice that of the wheel *q*.

The isolated chamber *h* in which the sleeve *d* works, may be surrounded in the usual way by the center circulation system common to both the cylinder *a* and the removable head *c*.

The free suspension of the trunnions *d*', 20 *d*', instead of being effected by a rigid frame, may be effected by a jointed frame constituted, for instance, as shown in the diagrammatic Fig. 6, by two parallel rocking beams *e* having conjugated movements. For this purpose the ends of the rocking beam may 25 be pivoted to the forks of two eccentric

connecting rods *f*, *g*. The parallel rocking beams having conjugated movements, may, also, as shown in Fig. 7, be actuated each by a pair of links *f*', *g*'.

Having now described my invention what I claim as new and desire to secure by Letters Patent is:—

In an internal combustion engine, the combination with the working cylinder and the reciprocating piston, of an oscillating frame comprising two rods, a cylindrical sleeve mounted to move relative to said working cylinder and having openings adapted to register with openings in said working cylinder and pivotally suspended from said two rods intermediate between their ends, and connecting rods pivotally connected with the ends of said two rods, so as to impart a conjugated movement thereto, thereby actuating said sleeve.

In testimony whereof I have affixed my signature in presence of two witnesses.

LOUIS GUICHARD.
